(57) **CLAIM**

We claim the ornamental design for a dosing spoon, as shown and described.

DESCRIPTION

FIG. 1 is a perspective view of a dosing spoon.

FIG. 2 is a top plan view thereof.

FIG. 3 is a bottom plan view thereof.

FIG. 4 is a front elevation view thereof.

FIG. 5 is a rear elevation view thereof.

FIG. 6 is a side elevation view thereof; and,

FIG. 7 is an opposite side elevation view thereof.

The broken lines in the drawings illustrate environmental structure on the article and form no part of the claimed design.
